(57) **CLAIM**

The ornamental design for a carbon removal and polishing tool for rifle bolts, as shown and described.

DESCRIPTION

FIG. 1 is a top front perspective view of a carbon removal and polishing tool for rifle bolts, the top rear perspective view being the mirror image thereof;

FIG. 2 is a front elevational view thereof;

FIG. 3 is a right side elevational view thereof; the left side elevational view being the mirror image thereof; and,

FIG. 4 is a top plan elevational view thereof; the bottom plan elevational view being the mirror image thereof.
The tool is molded from a fiberglass filled polymer hard plastic material and the broken line in the center of the tool represents a parting line of the mold and forms no part of the claimed design.
